United States Patent

Des. 242,553
Patented Nov. 30, 1976

242,553

HIGH FIDELITY LOUDSPEAKER

Lester M. Pitre, Orleans Parish, La., assignor to
Innovative Electronics, Inc., Jefferson, La.

Filed Nov. 21, 1975, Ser. No. 634,290

Term of patent 14 years

Int. Cl. D14—01

U.S. Cl. D26—14 G

FIG. 1.

FIG. 2.

FIG. 3.

FIG. 4.

FIG. 5.

FIG. 1 is a front perspective of a high fidelity loudspeaker showing my new design;

FIG. 2 is a front perspective taken from the opposite side of FIG. 1;

FIG. 3 is a side elevation thereof;

FIG. 4 is a rear elevation thereof; and

FIG. 5 is a top plan view thereof, the undisclosed bottom being a mirror image of the top.

I claim:

The ornamental design for a high fidelity loudspeaker, as shown and described.
